UNITED STATES PATENT OFFICE.

WALTER STURGES, OF LOS ANGELES, CALIFORNIA, ASSIGNOR TO MILON J. TRUMBLE,
OF LOS ANGELES, CALIFORNIA.

MILK-BOTTLE CONTAINER.

1,227,214.

Specification of Letters Patent. Patented May 22, 1917.

Application filed October 9, 1915. Serial No. 55,076.

To all whom it may concern:

Be it known that I, WALTER STURGES, a citizen of the United States, residing at Los Angeles, in the county of Los Angeles and State of California, have invented a new and useful Milk-Bottle Container, of which the following is a specification.

My invention relates particularly to the distribution and retail sale of milk, especially as carried on in glass bottles, or similar containers. Milk is commonly distributed in glass bottles, the filled bottles being delivered at the residence of the user at an early hour in the morning, empty bottles being taken away by the dairy company at the same time. As the cost of the container, or bottle, is about equal to the cost of the milk delivered, it is quite important that the dairy company should receive an empty bottle in exchange for the full one, as they are commonly paid only for the milk delivered. The householder will, however, often forget to put out the empty bottles, or the empty bottles will be stolen before the dairyman arrives. The losses through non-return of empty bottles is a considerable item in the expense of any dairy company, and the principal object of my invention is to do away with this loss.

There is also a considerable loss of milk, due to the filled bottles being stolen, this being a comparatively easy matter in the city when the milk is left at the residence of the user long before the members of the household have arisen. A further object of my invention is to prevent such loss of milk and filled bottles.

The fundamental idea behind my invention is to provide means for securing the bottles so that a bottle can only be removed by the insertion of another. That is to say, the only way a householder can get the filled bottle of milk is by delivering to the device an empty bottle to take its place, and the only way that the dairyman, or others, can remove the empty bottle is by the substitution of a filled bottle. This, I believe, to be a basic conception, the following struc-

ture being described as one convenient means by which the conception can be carried out.

In the drawings which are for illustrative purposes only:

Figure 1 is a sectional plan showing the apparatus in its gripping position.

Fig. 2 is a view of the entrance end of the container showing the position of parts during the insertion of a bottle.

Fig. 3 illustrates the exit end of the apparatus in its release position.

Fig. 4 is a sectional elevation on a plane represented by the line x^4-x^4 of Fig. 1.

Fig. 5 is a partial section on a plane represented by a line x^5-x^5 of Fig. 1.

In the form of my invention illustrated in these drawings a case 11 is provided, this case having an entrance opening 12, and an exit opening 13, of sufficient size to allow a standard milk bottle, or similar container, to be passed therethrough. Located at either end of the case are stiffening members 14 encircling the ends of the case. Shelf members 15 preferably of angle iron section are secured inside the case 11 to the stiffening members 14, extending longitudinally of the case. Pivoted on screws 16 which are secured to the shelf members 15 are a pair of gripping levers 17, these levers having gripping fingers 18 formed on the opposite end from the screws 16, the gripping fingers 18 being cut away as shown at 19 in such a shape as to inclose and grip a bottle, such as that shown in dotted lines at 20 in Fig. 1. Springs 21 engage the flanges 22 of the shelf members 15, and engage pins 23 secured in the gripping members 17, guided by small strap members 24 which are also secured to the shelf members 15. The springs 21 are so formed and disposed that they tend to push the gripping levers 17 into their gripping position as illustrated in Fig. 1. Located on the upper side of the gripping lever 17 are small rectangular pins 25, these pins being engaged in the locking position of the lever 17 by catches 26, the catches 26 being guided by bolts 27 secured to the shelf member 15. The catches 26 are

pivoted on release members 29, the release members 29 being pivoted on pins 30 secured to the lever 17. Trigger members 31 are secured at 32 to the gripping lever 17 being so formed that they drop in behind and catch on projections 33 formed on the members 29. Star wheels 40 are also pivoted on the screws 16, being of such a size and so disposed that they will allow a milk bottle, or 10 similar container, illustrated in dotted lines at 41, to pass therebetween. Ratchets 42, engaged by pawls 43, actuated by springs 44, prevent the star wheels 40 from turning in a direction opposite to the arrows 45 of 15 Fig. 1.

The method of operation of the invention is as follows: A bottle or other suitable container being inserted through the entrance opening 12 passes between the star wheels 20 40, and between the gripping levers 17. The bottle lifts the members 31 and strikes against the projections 33 of the levers 29, throwing the catch 26 into the position illustrated in Fig. 3. The gripping levers 17 are 25 then thrown in the position shown in Fig. 3, the pins 25 passing into slots 50 formed in the catches 26. The bottle can then be moved forward into the position shown at 20 in Fig. 1, and the gripping lever 17 can 30 be released, the springs 21 forcing the gripping levers into the position shown in Fig. 1. This operation is only necessary upon first using the device, the subsequent operation being as follows: The bottle 20 is firmly 35 gripped by the gripping levers 17 which are locked by the catches 26, these catches being held in their locked position by means of a spring 53 secured thereto, and secured at 54 to the flanges 22 of the shelf 15. When it 40 is desired to remove the bottle 20, this bottle being either a filled or an empty one, the dairyman, or the householder inserts the second bottle 41, which bottle passes through the star wheels 40, and is immediately locked 45 as shown in Fig. 2 so that it can not be withdrawn. The bottle 41 is then passed forward lifting the members 31 which normally lock the release members 29, and immediately thereafter engaging the levers 17 50 pushing them outwardly, and throwing the catches 26 into the position illustrated in Fig. 3. The bottle 20 can now be withdrawn and the bottle 41 can be passed up into the position formerly assumed by the bottle 20, 55 being locked in place by the gripping levers 17 which are forced into gripping positions by the springs 21. The object of the members 31 is to render the operation of the members 29 somewhat difficult by anyone 60 tampering with the container.

The ratchet 42 and pawl 43 are provided to prevent anyone from passing a bottle into the container a sufficient distance to release

the last bottle and then withdrawing the first bottle. The shell 11 extends completely 65 over the tops of both bottles so that the operation of the device is masked and the mechanism is partially protected against meddling persons. The top also protects the tops of the bottles keeping dirt and dust 70 from settling therein, and preventing them from being tampered with by cats or dogs in the neighborhood.

I claim as my invention:—

1. In a milk bottle container, a case having 75 a central opening large enough to allow a milk bottle to pass therethrough, gripping levers located on either side of said opening and so arranged that they will grip a milk bottle near the exit of said opening, catches 80 for locking said gripping levers in the grip position, and means by which said catches are released by a second bottle entering said opening.

2. In a milk bottle container, a case having 85 a central opening large enough to allow a milk bottle to pass therethrough, gripping levers located on either side of said opening and so arranged that they will grip a milk bottle near the exit of said opening, catches 90 for locking said gripping levers in the grip position, means by which said catches are released by a second bottle entering said opening, and means for preventing said second bottle from being withdrawn from said 95 opening.

3. In a milk bottle container, a case having 100 a central opening large enough to allow a milk bottle to pass therethrough, gripping levers located on either side of said opening 105 and so arranged that they will grip a milk bottle near the exit of said opening, catches for locking said gripping levers in the grip position, means by which said catches are released by a second bottle entering said opening, star wheels located on either side of the entrance to said opening and of such a size and shape that they engage said second bottle as it enters said opening, and means for locking said star wheels so as to 110 prevent a bottle from being withdrawn through the entrance to said opening.

4. In a bottle holding and locking device comprising a casing having a bottle slot 115 therein, said slot being just wide enough to allow the neck of a bottle to slide therethrough; a grip plate pivoted to said casing and so shaped and placed that it will engage and restrain the neck of a bottle which is directed into engagement with said grip plate by said slot; and means by which a second bottle upon entering said slot will cause said grip plate to release said first named bottle.

5. A bottle holding and locking device 125 comprising a casing having a bottle slot

therein, said slot being just wide enough to allow the neck of a bottle to slide therethrough; a grip plate pivoted to said casing and so shaped and placed that it will engage and restrain the neck of a bottle which is directed into engagement with said grip plate by said slot; means by which a second bottle upon entering said slot will cause said

5 grip plate to release said first named bottle, and means for preventing the withdrawal 10 of said second bottle from said slot.

In testimony whereof, I have hereunto set my hand at Los Angeles, California, this 2nd day of October, 1915.

WALTER STURGES.
